SUPERVISORY SWITCH

John H. Derby, Scarsdale, N. Y.

Application May 16, 1930, Serial No. 452,894

1 Claim. (Cl. 177—311)

This invention relates to an electric switch adapted automatically to operate any electrical means, such as a gong or light or other means for indicating at a remote point, any change in the relative position of an operable element, or any tampering with the signal which might render it inaccurate or inoperative for giving correctly such indications.

My invention is particularly applicable in the field of fire prevention and is adapted to be applied in the case of valves in sprinkler systems or other apparatus designed to afford fire protection but which may in emergencies be rendered temporarily inoperative. By means of my electric switch responsible officials or others charged with the responsibility of keeping the protective devices ready for immediate operation, will be at once notified if the protective device is rendered inoperative. My invention is also designed to be self-protecting in that it will give immediate and distinctive notification of any tampering with it or of any breakage or injury to it which might impair the value of the signals which it gives respecting the condition of the protective apparatus.

Devices have been known and used prior to my invention which are responsive to movement of a guarded element so as to give an alarm when the guarded element is moved beyond predetermined limits. It has also been known prior to my invention that such a device could be made self-protecting by using a closed circuit in the normal relation of the parts and by making the alarm responsive to a break in the circuit. Such prior devices have been designed so that the movement of the guarded element beyond the predetermined limits causes the movement of a contact so as to break the circuit and give the alarm. As it is sometimes necessary to remove or repair these devices and since in every case such removal or repair will give the alarm, these prior devices fail of complete satisfaction because the alarm becomes too common and not solely indicative of the condition which is to be avoided. By my present invention I am able to control the circuit so as to give one alarm which is always indicative of the condition which the device is intended to guard against and another and distinctive alarm when there is any trouble in the device itself which would prevent its responding to the movement of the guarded element by giving the characteristic alarm.

In the accompanying drawings I have shown at Figure 1 a diagrammatic view illustrating the

mounting of the device constructed according to my invention on a gate valve;

Figure 2 a wiring diagram illustrating the method of transmitting the signals to remote points;

Figure 3 a cross section taken on line 3—3 of Figure 1 and illustrating a switch constructed according to my invention;

Figure 4 a side plan view of the switch taken on line 4—4 of Figure 3 showing the switch with the cover removed; and

Figure 5, a wiring diagram illustrating how a plurality of the switches according to my invention can be combined in a single circuit.

In Figure 1, I have shown the operating stem 10 of the gate valve as having a depression 11 cut in one side thereof. The ends of this depression, 12 and 13, serve as cam surfaces to move the follower 14 of the switch away from the axis of the valve stem if it is moved from the position in which the depression 11 is aligned with the follower 14. This depression 11 is positioned on the valve stem so that it comes into alignment with the follower 14 only when the valve is opened as required by its intended use, which is to be guarded by the switch.

The follower 14, as more clearly shown in Figure 3, is connected to a button 15 of insulating material and is pressed toward the valve stem 10 by means of a spring 16. Flat faces for engaging a wrench are cut on the side of the follower 14 as indicated at 50; and the end 51 of the follower 14 has similar flat faces for engaging a wrench. The end 51 is threaded into the body of the follower 14 and may be adjusted after the switch is in place to bring the follower into exact relation to the valve stem. A lock nut 53 secures the adjustment when made.

Above the button of insulating material 15 are mounted a series of spring contact members 17, 18, 19 and 20. These contact members are secured at their opposite ends to a post 21 by means of the screws 22 and are insulated from each other by suitable insulating blocks 23 and from the screws by insulating bushing 24. The contacts 17, 18, 19 and 20 are carefully shaped so that any movement of the button 15 away from the contacts will permit the separation of the contacts 17 and 18 and thus cause a breaking of the circuit which is shown in Figure 3 as closed. On the other hand, if the button 15 is moved toward the contacts and away from the axis of the valve stem the result would be to close the contacts 17 and 18 and thus to close a circuit between them which will at once give a distinctive

signal at any desired point. The contacts 19 and 20 are formed so that when they are free they are separated and both are above the position shown in Figure 3. When, however, the switch 5 is in operative position on the valve and a cover 25 is in position the spring contact 23 is pressed, by means of the insulating button 26 secured to the cover 25, against the spring contact 19 and in this way a circuit is closed through the contacts 19 and 20 and also the contact 19 is accurately positioned with respect to the contact 17.

In order to protect the contacts and the wiring against tampering a container 27 of which the cover 25 forms one side, surrounds the operative 15 part of the switch with the exception of the wiring from the contacts to the remote indicating means and also with the exception of the end of the cam follower 14. The wiring from the contacts is preferably enclosed in a suitable conduit 20 or metal sheath cable so that it also is safe from tampering. For this purpose a threaded opening 54 is provided for connecting such conduit or sheath. An insulating disk 55 having spaced holes for the entrance of wires from the conduit 25 or cable may be used at this opening. Obviously the container may be made also to include the cam follower. This, however, will ordinarily not be necessary since it is practically impossible to manipulate the follower so as to avoid the giving 30 of some signal when the valve is closed, either a signal of closing the valve or of tampering.

As shown in Figures 1, 3 and 4 the switch is advantageously secured to the yoke of the valve by three screws 28. In order to permit the adjustment of the switch to the proper position and to accommodate variation in various valves to which it may be applied the holes 29, through which these screws pass, are slotted. Two of these screws are within the casing 27 and thus 40 cannot be removed without giving a trouble signal.

In order to exclude so far as possible, dust and moisture which if admitted might impair the efficiency of the electrical contacts, felt gaskets 45 56, 57 and 58 are provided about the follower 14 between the cover 25 and the container 27 and about the screws 28. Plates 59 are positioned above the gaskets 58 having holes adapted to fit the screws 28 and form a bearing for the heads 50 of the screws. The gasket 56 about the follower 14 is of a highly elastic felt such that it will expand and contract with the movements of the follower and thus be operative as a gasket when the follower is pressed in, as required when in 55 operative relation in order to close the circuit between the contact members 17 and 18, but without offering any substantial resistance such as would prevent the movement of the follower to separate the contacts 17 and 18 when the device 60 is removed from its operative relation with the valve stem.

Referring more particularly to Figure 2, I have shown diagrammatically the contact members 17, 18, 19 and 20, together with the wiring connections and the remote indicating means. A battery or other source of current 30 is connected through the line 31 with the contact 18. When the button 15 is in the position indicating that the valve is open and the cover 25 is in position 70 on the container 27, a circuit is closed from the source of current 30 through line 31, the contact 18, the contact 17, the line 32, the resistance 33, the line 34, the contact 20, the contact 19, and the line 35 to the relays 36 and 37, and from 75 thence back through the line 38 to the battery.

The relay 36 is designed so that its armature is held up by the current passing through the circuit just described. An annunciator light 39 is also connected into this circuit but is not lighted by the small current flowing through the circuit when connected as just described. The relay 37 is designed so that its armature will not be held up by the current flowing through this circuit. 5

If now the valve should be closed so as to move the button 15 inwardly, the contact 17 would be 10 moved by it so as to close a circuit through the contact 17 to the contact 19 and thus the resistance 33 would be shunted out of the circuit and the current flowing through the circuit would be very substantially increased. With this increased 15 current flow the lamp 39 would be lighted and the relay 37 would be closed so as to operate an alarm gong 40 or any other suitable indicating means. Obviously instead of one gong a number of gongs at different points or a plurality of any 20 one or more kinds of indicating means might be used. The indicating means 40, whether one or many and whether of one or many kinds, should be characteristic so that it will at once indicate to those responsible for maintaining the protective apparatus in operative condition that the valve has been closed or partially closed. The lamp 39 is advantageously designed for a heavier current than is encountered in this circuit, so that danger of its burning out will be avoided. A red 30 glow of the lamp caused by the current less than that for which it is designed will be sufficient to give warning of the circuit condition.

Assuming now that someone should remove the cover 25 of the casing 27, either to adjust or repair the device or for the purpose of tampering with the device, the button 26 would be withdrawn and the contact 20 would be permitted to spring away from the contact 19. Thus the circuit would be broken, the armature of the relay 40 36 would drop and would close the circuit through the line 41 so as to operate the trouble gong 43. The ringing of the gong may be silenced by throwing the switch 42, but this would close the circuit through the trouble lamp 44. The lamp 44 re-45 mains lighted so long as the trouble gong is switched out of the circuit and whether the armature of the relay 36 is up or down.

If instead of removing the cover 25 to tamper with the apparatus the entire supervisory switch 50 should by some means be pried loose, the button 15 would recede from its operative position under the influence of the spring 16 and the contact 17 would then be permitted to separate from the contact 18. The circuit would thus be broken 55 with the same effect as has been described above in the case where the cover was removed. Similarly, if the wires should be cut or broken or if the normal supervisory current is interrupted in any way the relay 36 would be deenergized, its 60 armature would fall and its contacts be closed which in turn would give the trouble signal.

In the drawings I have shown a second trouble alarm circuit for supervising the valve closing alarm circuit. This includes a high resistance 65 relay 46 with its winding connected to the contacts of the relay 37 and normally holding its armature up and its contacts open. In case of injury to the alarm circuit the armature of the relay 46 will drop and close a circuit through the 70 trouble gong 43; or, if desired, through a separate trouble gong. The use of this additional precaution is not essential to the operation of my device.

One or more of the valve switches may be con- 75

nected in parallel into the same circuit and in this case a single resistance 33 and a single set of relays and alarms may be used for the entire circuit, as shown, for example, in Figure 5.

5 Also a high resistance relay may be substituted for the fixed resistance 33 as illustrated in the drawing and this relay may serve the function of the trouble relay 36.

Instead of using two separate relays 36 and 37, 10 as illustrated in the drawing or as suggested in the preceding paragraph, a single relay 37a such, for example, as that described and claimed in the patent of myself and G. H. Leach, No. 1,863-836, dated June 21, 1932, may be used. A single 15 relay used for this purpose must respond differently for different current strengths so that it may close one circuit at one current strength and another circuit at another current strength.

It will be understood that instead of a cam 20 follower other means might be used for effecting the operation of the switches or contacts in response to movement of the guarded element and many other changes may be made within the scope of my invention, which will be apparent 25 to those skilled in the art from the above description.

It will be readily understood from the foregoing 30 that I have provided a substantially self-protecting supervisory switch which will give immediate notice at one or more remote points of any operation of the guarded member and a different distinctive signal of any tampering with or injury to the switch or its circuit. It is thus possible to effect some automatic operation in response 35 to the operation of the guarded element, and to call an attendant in case of tampering with or injury to the device. It will be also readily understood that my invention is not limited to the particular device described above and particularly 40 that it is applicable to many other kinds of operable mechanisms or members than the particular gate valve illustrated.

What is claimed as new is:

A device responsive to movement of a guarded element comprising a guarded element movable along a limited path, said element being provided with a cam face having low and high portions, 5 a follower, a container, means for slidably mounting said follower in one side of said container so that it projects therein, a removable cover for the said container, means holding said container accurately positioned adjacent said guarded element, so that in the normal position of the guarded element said follower engages said cam face at the low portion thereof, means resiliently pressing said follower against said cam face, an alarm actuating circuit including 10 a source of current and means affecting the current flow through said circuit arranged in series therein, two pairs of resilient contacts arranged in series in said circuit one on each side of said current affecting means, means mounting said 15 contacts within said container in the path of movement of said follower so that in the normal position of said guarded element the follower presses one of said pairs into electrical contact, means on said cover for pressing said other pair 20 of contact into electrical contact, said pairs of contacts being mounted in such a position with respect to each other that movement of said guarded element causes said follower to move one 25 contact of one pair into engagement with one contact of said other pair to short-circuit said 30 current affecting means, a main alarm circuit and auxiliary trouble alarm circuit, means in said alarm actuating circuit for closing said main alarm circuit when said current affecting means 35 is short-circuited, and means in said alarm actuating circuit for closing said trouble alarm circuit when said alarm actuating circuit is opened at either of said pairs of contacts.

40 JOHN H. DERBY.
